Primary Examiner — Shannon W Morgan*Assistant Examiner* — Altaira J Swangin(74) *Attorney, Agent, or Firm* — Tucker Ellis LLP(57) **CLAIM**

The ornamental design for a bowl, as shown and described.

DESCRIPTION

FIG. 1 is a top, front, left perspective view of a bowl showing our new design.

FIG. 2 is a front view thereof.

FIG. 3 is a rear view thereof.

FIG. 4 is a right side view thereof.

FIG. 5 is a left side view thereof.

FIG. 6 is a top view thereof.

FIG. 7 is a bottom view thereof; and,

FIG. 8 is another top, front, left perspective view of the bowl of FIGS. 1–7 with the environment removed for ease of illustration.

The broken lines, in FIGS. 1–7, depict environmental subject matter that forms no part of the claimed design.

1 Claim, 5 Drawing Sheets# US D862,990 S
